UNITED STATES PATENT OFFICE.

FRIEDRICH BARTLING, OF MUNICH, GERMANY.

GAS-TIGHT SEAL FOR RELATIVELY-MOVING PARTS OF OVENS.

Application filed May 16, 1927, Serial No. 191,913, and in Germany January 15, 1927.

For the purpose of effecting a gastight closure or seal between relatively movable parts of ovens and the like for instance, between fixed and moving parts thereof, numerous varieties of so-called sand channels have, as is well known, been employed. These sand channels consist generally of a gutter of U-section, located on one of the oven members and substantially filled with sand, into which dips a web plate or rib secured to the other oven member. In this manner gas tight closure is effected between the interior of the oven and the external atmosphere, or between two different compartments of the oven, without impairing the relative mobility of the several oven parts involved.

Such a device is particularly adapted for application to the so-called revolving annular sole type of ovens, in which, as is well known, an annular oven chamber open at the bottom, has that opening closed by a rotating plate which functions as the working sole plate. Obviously a gastight and heat proof closure must exist between the wall of the oven and the rotating plate, in order that the oven gases may not escape. Generally a sand channel will be employed for this purpose.

So long as the dipping web proceeds regularly and without deviation between the walls of the sand channel no obstruction or other disturbance can take place within said channel. It is, however, impossible to secure such regular movement of the web; in practice oscillatory movements are set up and the web thus moves laterally within the channel, that is to say, in a direction perpendicular to the axis of rotation where a rotary web member is in action. Such irregular movement, which it is practically impossible to avoid in the moving parts of large and heavy ovens, gives rise to secondary disturbances which occasion considerable trouble in working. Thus, when the dipping web is so displaced, it presses the sand to one side of the channel, so that the depth of the bed of sand on one side of the web is diminished while on the other side the sand piles up against the wall of the channel. The result of this generally is to cause the sand to overflow from the channel onto adjacent parts where its presence is undesirable. At the same time, the amount of sand in the channel is, of course, diminished, so that the

efficacy of the seal is reduced also and has to be restored by replenishing the sand bed.

It is the object of the present invention to overcome these objections.

According to the invention, a gas-tight seal for relatively movable oven members, with a sand channel and a web dipping therein is characterized by the fact that the lower part of the cross-section of the sand channel is bellied out to a pear-shape. This formation may be completed by so making the channel section that above the bellied portion there is a narrowed or necked region. At the same time, the dipping web is pierced from side to side with suitable apertures, for instance a row of holes may be provided in it.

The shaping of the cross-section of the sand channel in the manner above described results, in the first place, in preventing the sand from overflowing from the channel when the dipping web moves laterally. At the same time the sand which tends to pile up at one side of the web is forced to pass through the apertures aforesaid to the opposite side of said web. Thus there results a continuous equalization of the quantities of sand on each side of the web, while overflow and irregular distribution of the sand in the channel are completely avoided.

An example of a construction according to the present invention is illustrated in the accompanying drawing, wherein:

Fig. 1 shows a sand channel with dipping web constructed according to the invention while,

Fig. 2 shows an example of the application of said invention to an oven of the annular rotating sole type.

As shown in Fig. 1, the oven sealing means consists of a channel *a* and a web *b*, the channel being associated with one of two relatively movable oven parts and the web with the other of these parts. The channel *a* is filled with sand so as to provide a gas-tight closure on both sides of the web *b*. Normally, when the two oven parts move relatively to one another, the web *b* will be displaced in a direction parallel to the channel walls (see arrow *c*) but when irregular movements or oscillations take place lateral digression of the web, in the sense indicated by arrow *d* are set up. If the web *b* be displaced, for instance in the right handed direction of the arrow *d*, it forces the sand to

the right of it up against the right hand wall of the channel *a*. If the ordinary U-shaped sand channel were employed the sand would, in these circumstances, be forced upwards until it ran over the side of the channel.

In the device of the present invention the cross-section of the sand channel immediately above its bottom *e* is bellied out, as at 10 *f* and above this is a portion *g* of narrowed or necked cross-section. By reason of this formation overflow of the sand is so impeded as to render it almost impossible. The web *b* is provided, adjacent its lower 15 edge, with a series of perforations *h*. As soon as the sand, by reason of lateral movement of the web *b*, is forced up against the wall of the channel, it gets squeezed through the perforations *h* to the other side of the 20 web, thus securing a quicker equalization of the quantities of sand on opposite sides of said web.

In the constructional example according to Fig. 2, the improved sand channel arrangement is shown in its application to an oven of the annular rotating sole type, though it is to be understood that the details of this oven form no part of the present invention. The stationary, annular oven chamber *k* has 25 an open bottom which is closed by the rotating sole plate *l* which is supported at its edges by carrier rings *m* running on rollers *n*. The rotating sole *l* is heated from beneath by a heating flue *o*. Between the sole *l* and the heating flue *o*, on the one hand, and between said sole plate and the oven chamber *k*, on the other hand, sand channel seals are 30 arranged. These consist severally of the sand channels *a*, *a'* with corresponding webs *b*, *b'*. The sand channel *a* is arranged on the stationary heating flue *o* and the web *b* on the rotating sole *l*. To this latter is also secured the channel *a'* while the web *b'* is arranged on the fixed oven wall *k*.

It is obvious that, so long as the rotating sole *l* runs true in its circular path, there is 45 no displacement of the beds of sand in the sand channels. Such absolutely true rotary motion is, however unattainable and oscillations take place which result in lateral 50 movements of the webs. The sand in the channels is then squeezed between the webs and the channel walls and would overflow but for the equalizing action due to the particular construction and arrangement of 55 channel and web as hereinbefore described.

Having now particularly described and ascertained the nature of my said invention and in what manner the same is to be performed, I declare that what I claim is:— 60

1. A gas tight closure or seal for interposition between relatively movable members of ovens and the like, comprising a sand channel mounted on one of said members, the walls of said channel converging toward each other at the top so the channel has a substantially pear-shaped cross-section, sand in said channel, and a web connected to the other member and dipping into the sand, so that during relative movements of said 65 web and channel at a right angle to the direction of the relative movement of the members, the converging walls of the channel prevent the web from forcing sand from the channel. 75

2. A gastight closure or seal as in claim 1, in which the web is provided with apertures beneath the level of the sand, through which the sand may pass from one side of the web to the other during such movements 80 at a right angle.

3. A gastight closure or seal for interposition between relatively rotating members of ovens and the like, comprising an annular sand channel mounted on one member, the walls of the channel converging toward each other at the top, sand in said channel, and an annular web connected to the other member and dipping into the sand, the sand permitting relative radial movements of said channel and web with respect 85 to their axis of relative rotation during 90 which the convergent walls of the channel prevent the sand from being pushed therefrom. 95

4. A gastight closure or seal for interposition between relatively rotating members of ovens and the like, comprising an annular sand channel mounted on one member, sand in the channel, and an annular web connected to the other member and dipping into the sand, said web having holes therethrough adjacent its lower end and beneath the sand so that when said web and channel have a relative radial movement with respect to 100 their axis of relative rotation, sand may pass through certain of said holes from one side of the web to the other. 105

In testimony whereof I have signed my name to this specification.

FRIEDRICH BARTLING.
